UNDERREAMER

Emmett J. Roe, Wichita, Kans., assignor of
one-half to C. E. Glamann

Application March 25, 1933, Serial No. 662,764

13 Claims. (Cl. 255—75)

My invention relates to improvements in underreamers and particularly to the type of underreamer disclosed in my Patent #1,517,586, granted December 2, 1924.

5 In the past, it has been the practice when reaming well holes, to first raise the casing before commencing the operation of reaming, but at the present time it is desirable to ream the hole without raising the casing, and therefore, it is
10 10 an object of the present invention to change the construction of the underreamer disclosed in my prior patent to permit the reaming of well holes without having to raise the casing.

15 A further object of the invention resides in the manner of mounting the cutters in the slots of the reamer, to cause canting of the cutters when in a contracted position, whereby the cutting edges are projected into operative engagement with the wall of the hole.

20 Another object of the invention is to provide a device of the above-mentioned character which is simple and durable in construction, reliable and efficient in operation and inexpensive to manufacture.

25 Other objects and advantages of the invention will be apparent during the course of the following description.

In the accompanying drawing, forming a part 30 of this specification and in which like numerals are employed to designate like parts throughout the same,

35 Fig. 1 is a longitudinal sectional view of the reamer, showing the position of the cutters when the reamer is being lowered into the well casing.

Fig. 2 is a similar view showing the initial position of the cutters, when the reaming of the hole is commenced, and.

40 Fig. 3 is a similar view showing the position of the cutters when fully expanded.

45 In the drawing, wherein for the purpose of illustration, I have shown a preferred embodiment of my invention, the numeral 5, denotes the body of the reamer having opposed longitudinal ways or slots 6, at its lower end to receive the reaming cutters 7, adapted to move longitudinally of the slots. The bottom of the slots, approximately midway their length, are provided with an oblique shoulder 8, placing the lower portion 9 of the slots on a plane nearer the axis of the body, then the upper portions 10. The sides of the slots 6, are undercut forming guide-ways 11 and flanges 12, for guiding the movement of the cutters, the guide ways at their lower ends being 50 relatively wider than at their upper ends to per-

mit passage of the cutters from the lower ends of the slots to the upper ends and also permit limited rocking movement of the cutters while in the lower ends of the slots. The sides of the cutters 7, are provided with longitudinal recesses 5 13, to receive the flanges 12, the recesses being relatively wider than the flanges and having their inner walls at their lower ends, beveled, as at 12', to permit free rocking movement of the cutters when in a contracted position.

10 The upper ends of the reaming cutters terminate in oblique faces 14, adapted to abut against the upper ends or sockets 15 of the slots, when the cutters are fully expanded, as shown in Fig. 3. The faces 14, adjacent the inner side 15 of the cutters are beveled, as at 16, and the inner edge of the faces serve as a fulcrum for the cutters when abutting the base of the shoulder 8, as shown at 17, in Figs. 1 and 2. To conform with the curvature of the hole the outer surface 20 of the cutters is curved transversely and at its lower edge projects outwardly to provide a cutting edge 18. The bits adjacent their upper ends are provided with transverse rectangular openings 19, extending through the cutters, adapted to receive the ends of the flat rectangular cross bar 20 and a recess 21, which is wider than the openings 19, is formed at each outer end of the openings to receive the heads of the pins 22 fitted in the ends of the cross bar. Thus, it is seen the 30 cutters are loosely connected together by the cross bar, and are limited in their movement on the cross bar by the pins 22, the heads of which project beyond the sides of the cross bar.

35 The ends of the cross bar 20 fit loosely in the openings 19, and the inner ends of the openings are flared, as at 23, to permit limited rocking movement of the cutters on the cross bar. The cross bar 20, passes through the longitudinal slot 24, which intersects the central bore 25 of the 40 reamer body 5 and is connected to the lower end of the plunger 26, slidably mounted within the bore. The upper portion of the bore 25 is enlarged to receive the expandable coil spring 27 mounted on the plunger, which constantly exerts 45 an upward tension on the plunger. When inserted into the well casing 28, the cutters are in the position shown in Fig. 1, and it will be seen the heel of the cutters rides against the casing wall. In this position, the upper edge of the cross 50 bar 20, at its ends, contacts with the top of the openings 19, adjacent their outer ends and through the tension of the spring 27, on the plunger 26, the cutters are docked on their fulcrums 17, so that when the cutters are below the 55

lower end of the casing and the reamer is reciprocated, the cutting edges 18 are projected into operative engagement with the wall of the hole. The cutters remain in the position, shown 5 in Fig. 2, during the initial reaming operation, and as the well hole is enlarged the cutters are gradually canted to keep the cutting edge in engagement with the wall of the hole and when the beveled portion 16 of the faces 14 contact with 10 the face of the shoulder 8, the cutters ride up the shoulders and move to fully expanded position, as shown in Fig. 3.

In operation, when the cutters are lowered beyond the end of the well casing 28, the spring 15 tension on the cross bar 20 will cause the cutters to be rocked on their fulcrums 17, so as to assume the position shown in Fig. 2. In this position, the beveled edges 16 of the cutters abut against the shoulder 8 and the cutting edges 18 20 are projected into operative cutting engagement with the walls of the hole to be reamed. Upon initial operation of the tool the walls of the hole prevent the cutters from moving to fully expanded position, but as the diameter of the hole 25 increases the beveled edges 16 ride up the oblique shoulders 8, until they are free to move to normal operative position, as shown in Fig. 3. It is only proposed that the cutters remain in the position shown in Fig. 2, during the initial operation 30 of the reamer, which permits the hole to be reamed without first raising the well casing.

It is to be understood that the form of my invention herewith shown and described is to be taken as a preferred example of the same and 35 that certain changes in the shape, size and arrangement of the parts may be made without departing from the spirit of the invention or the scope of the subjoined claims.

Having thus described my invention, I claim:—

1. In an expandable underreamer, the combination 40 of a reamer body having longitudinal ways, means slidably and rockably mounting cutters in the ways of said body, means for moving said cutters upwardly in the ways and means intermediate the length of the ways for causing the lower ends of the cutters to be swung outwardly into expanded operative position.

2. In an expandable underreamer, the combination 45 of a reamer body having longitudinal ways, means slidably and rockably mounting cutters in the ways of said body, means for moving said cutters upwardly in the ways and abutments intermediate the length of the ways against which the upper ends of said cutters are adapted to 50 fulcrum whereby the lower ends of the cutters are swung outwardly into expanded operative position.

3. In an expandable underreamer, the combination 55 of a reamer body having longitudinal ways provided with sockets at their upper ends, means slidably and rockably mounting cutters in the ways of said body, yieldable means for moving said cutters upwardly in the ways and abutments intermediate the length of the ways against which the upper ends of said cutters are adapted to 60 fulcrum whereby the lower ends of the cutters are swung outwardly into operative position, said cutters being adapted to ride over said abutments and move upwardly into the sockets after initial 65 operation of the reamer.

4. In an expandable underreamer, the combination 70 of a reamer body having longitudinal ways provided with sockets at their upper ends, means slidably and rockably mounting cutters in the 75 ways of said body, yieldable means for moving

said cutters upwardly in the ways and means intermediate the length of said ways for momentarily arresting the upward movement of said cutters and cause the lower ends of the cutters to swing outwardly into expanded operative 5 position.

5. In an expandable underreamer, the combination of a reamer body having longitudinal ways, cutters movable in the ways, a cross bar 10 slidably and rockably mounting said cutters in the ways and means in the ways of said body against which the upper ends of said cutters are adapted to fulcrum whereby the lower ends of the cutters are swung outwardly into expanded operative position. 15

6. In an expandable underreamer, the combination of a reamer body having longitudinal ways, a shoulder formed in the base of each of said ways, cutters slidably and rockably mounted in said ways and adapted to have their upper ends 20 abut against said shoulders and means for moving said cutters upwardly in said ways against said shoulders, the upper ends of said cutters being adapted to fulcrum against said shoulders to swing the lower cutting edges outwardly into 25 expanded operative position.

7. In an expandable underreamer, the combination of a reamer body having longitudinal ways, cutters slidably and rockably mounted in said ways, and means formed in the base of said ways against which the upper ends of said cutters 30 are adapted to fulcrum when moved upwardly in said ways, whereby the lower cutting edges are swung outwardly into expanded operative position. 35

8. In an expandable underreamer, the combination of a reamer body having longitudinal ways, cutters slidably and rockably mounted in said ways, means formed in the base of said ways against which the upper ends of said cutters are 40 adapted to fulcrum and means for moving said cutters upwardly in said ways into fulcrumed engagement with said first mentioned means, whereby the lower ends of said cutters are swung outwardly into expanded operative position. 45

9. In an expandable underreamer, the combination of a reamer body having longitudinal ways, said ways having the upper portion of their base off-set outwardly from the lower portion and connected by a downwardly and inwardly inclined shoulder, and means slidably and rockably mounting cutters in said ways, the top inner edges of said cutters being adapted to fulcrum against the shoulders of said ways when said cutters are moved upwardly, whereby the lower ends of the cutters are swung outwardly into expanded operative position. 50 55

10. In an underreamer, the combination of a reamer body having longitudinal ways, abutments formed in the base of said ways intermediate their length, cutters movable in said ways, a cross bar extending through openings in said cutters slidably and rockably mounting said cutters in said ways, and means exerting an upward pull on said cross bar to move said cutters upwardly in said ways, the inner upper edge of said cutters being adapted to fulcrum against said abutments, to initially expand the lower ends of the cutters to operative position, before moving to the upper ends of said ways. 60 65 70

11. In an expandable underreamer, the combination of a reamer body having longitudinal ways, the bottom of said ways intermediate their length being provided with transverse shoulders, cutters slidably and rockably mounted in said 75

ways, the inner top edges of said cutters being adapted to fulcrum against said shoulders and means for exerting an upward tension on said cutters, whereby the cutters are rocked on their fulcrums to swing the lower cutting edges of said cutters to an expanded operative position.

12. In an expandible underreamer, the combination of a reamer body having longitudinal ways, said ways having the upper portion of their base off-set outwardly from the lower portion and connected by a downwardly and inwardly inclined shoulder, cutters slidably and rockably mounted in said ways, and tensioning means for exerting an upward pull on said cutters, the shoulders of 10 said ways serving as a fulcrum for the upper ends of said cutters when the cutters move upwardly whereby the lower ends of the cutters are rocked to swing the cutting edges outwardly into expanded operative position.

13. In an expandible underreamer, the combination of a reamer body having longitudinal ways, oblique shoulders formed in the base of said ways, intermediate their length, cutters slidably and rockably mounted in said ways, the upper face of said cutters having inner beveled edges, a cross bar extending through openings in said cutters having the outer ends of its upper edge in contact with the top of the openings adjacent the outer face of said cutters, and tensioning means for exerting an upward pull on said cross bar whereby the inner edge of the top faces of the cutters are caused to fulcrum against said shoulders, whereby the lower ends 15 of the cutters are swung outwardly to expanded operative position.
